UNITED STATES PATENT OFFICE.

LLOYD ESPENSCHIED, OF HOLLIS, NEW YORK, ASSIGNOR TO AMERICAN TELEPHONE AND TELEGRAPH COMPANY, A CORPORATION OF NEW YORK.

MULTIPLE BALANCING ARRANGEMENT FOR MULTIPLEX TRANSMISSION.

Application filed August 29, 1919. Serial No. 320,661.

To all whom it may concern:

Be it known that I, LLOYD ESPENSCHIED, residing at Hollis, in the county of Queens and State of New York, have invented certain Improvements in Multiple Balancing Arrangements for Multiplex Transmission, of which the following is a specification.

This invention relates to signaling systems and more particularly to multiplex systems in which high frequency carrier currents are used for the transmission of signals.

One of the objects of this invention has reference to the provision of a multiplex system in which the common transmission line over which a plurality of signals may be simultaneously transmitted is balanced by a single artificial line or balancing network. Another object of the invention has reference to the provision of a multiplex system in which each transmitter is so associated with the common transmission line that energy therefrom impressed upon the transmission line will be not only substantially without effect upon the receiver at the same station, but will also be substantially without effect upon the receivers associated with other channels. Other and further objects of the invention will more fully appear hereinafter as the description of the invention proceeds.

The objects of this invention may be attained by providing multiple connections between the common transmission circuit and its balancing artificial line or network and separately associating a receiving and a transmitting element for each channel with each multiplex connection in such a manner that one of the two elements will be inductively connected to the corresponding multiple connections, while the other of said elements will be connected to neutral points of said multiple connection with respect to the first element. It will be understood, of course, that the arrangements of this invention may be applied to any form of multiplex system and are equally applicable to multiplex transmission over wire transmission lines or to multiplex transmission in connection with radio telephony and teleraphy.

The invention may now be more fully understood by reference to the following de-

scription, when read in connection with the accompanying drawings, Figures 1 to 8 inclusive, of which are simplified diagrams of a number of embodiments of the invention, while Figs. 1^a to 4^a, inclusive, illustrate how the antenna may be replaced by a wire transmission line in circuits embodying the present invention.

Referring to Fig. 1, A designates an antenna, such as is used in radio telephony or telegraphy and N designates an artificial line or network adapted to balance the antenna or other form of transmission circuit over which a plurality of signals may be simultaneously transmitted. The antenna is associated with the artificial line or network N through a plurality of multiple connections 1—1', 2—2' and 3—3' with each of which corresponding transmitting and receiving arrangements are associated. The antenna A in this arrangement may obviously be replaced by an ordinary wire transmission line as indicated in dotted lines at L in Fig. 1^a.

The receiving element or device conventionally indicated at R₁ is associated with the corresponding multiple connection 1—1', through a selective means herein illustrated as a tuned circuit and through a transformer arrangement 11 having windings in each of the sections 1 and 1' of the multiple connection. The transmitting device or element conventionally indicated at T₁ is bridged between the sections 1 and 1' of the multiple connection at the mid points of the windings of the transformer 11 so as to be neutral with respect to the receiving device R₁. It will be understood, of course, that the transmitting and receiving devices or elements T₁ and R₁ may be of any desired character and may include any of the well known arrangements for modulation, demodulation and filtering employed in connection with radio telephony or telegraphy or other forms of multiplex carrier systems.

Receiving devices or elements R₂ and T₂ are similarly associated with the multiple connection 2—2', through the transformer 12, while the receiving devices or elements T₃ and R₃ are likewise associated with the multiple connection 3—3' through the transformer 13. It will be observed that the con-

nections of the various transmitting and receiving devices are such that energy applied from any transmitter, such as T_1 to the common transmission circuit, such as antenna A or the line L will be substantially without effect upon, not only the corresponding receiver R_1 , but also the receivers R_2 and R_3 associated with other multiple connections.

- An alternative arrangement is illustrated 10 in Fig. 2 in which the invention is shown as applied to a system employing a ground return as distinguished from a full metallic system. Similar elements in the two diagrams are designated by the same reference 15 characters. In Fig. 2 it will be noted that each of the transmitters T_1 , T_2 and T_3 are connected to ground instead of metallic return conductors of the multiple connections. The balancing artificial line or network N 20 is also connected directly to ground instead of being connected through metallic conductors of the multiplex connections to the return wires of the transmission line or to the grounded section of the antenna. In 25 case the antenna A' of Fig. 2 is replaced by a transmission line, such as L_1 , it will be understood that such transmission line will be connected to ground at its opposite end through apparatus similar to that illustrated 30 in Fig. 2, so that a grounded return will be employed by the transmission line. The operation of the arrangement of Fig. 2 is similar to that of Fig. 1, and need not be further described.
- 35 Fig. 3 shows an arrangement somewhat similar to Fig. 1, but employing filtering arrangements in the multiple branches in order to provide for the separation of the several channels instead of providing for 40 frequency separation by locating filters in the local transmitting and receiving circuits. It will be noted that the multiple branches 1, 2 and 3 contain filters which are conventionally indicated at F_1 , F_2 and F_3 . 45 These filters may be simple tuned circuits as in Fig. 1, but where a carrier current is modulated by a low frequency signal involving a band of frequencies of considerable width, it is preferable to use broad 50 band filters of the type illustrated in United States patents to George A. Campbell Nos. 1,227,113 and 1,227,114 dated May 22, 1917. Balancing means F'_1 , F'_2 and F'_3 are included in the multiple balancing circuits 1', 55 2' and 3' for the purpose of balancing the filters F_1 , F_2 and F_3 . The balancing means may be simply broad band filters identical in construction with the filters F_1 , F_2 and F_3 , or they may be networks of any character 60 having electrical characteristics simulating those of the filters. The transmitting and receiving circuits T_1 , R_1 , etc. may be of any character and where the invention is applied to a system employing carrier currents, these transmitting and receiving cir-

cuits will contain suitable modulating and demodulating apparatus as well as filters and amplifiers when desired. The operation of the arrangement of Fig. 3 is similar to that of Fig. 1 and need not be described. 70

Fig. 4 illustrates an arrangement similar to that of Fig. 3 but differing therefrom in that the multiple branches are connected in series instead of in parallel. In this figure, the multiple branches 1, 2 and 3, including the filters F_1 , F_2 and F_3 , are connected in series with each other and with the circuit leading to the line L or the antenna A as the case may be. Similarly the balancing multiple branches 1', 2' and 3', containing the filters F'_1 , F'_2 and F'_3 , are connected in series with each other and with the artificial balancing network N. The filters function, as in Fig. 3, to separate the frequencies into the proper channels. The operation is in 80 general similar to that of Fig. 3, and will be obvious without further description.

Fig. 5 illustrates a manner in which the principles of the invention may be applied to a multiplex system employing carrier currents. In this figure ML designates the main transmission circuit, which may be either a wireless antenna or an ordinary wire transmission line, while L_1 , L_2 and L_3 indicate low frequency signaling lines such as, for instance, telephone lines, the signals from which are to be superposed upon the main line ML. The main line ML is associated with the balancing artificial line or network MN through the bridge connections 1—1', 2—2', 3—3' etc., each of which bridge connections includes pairs of filters HF_1 , HF'_1 , HF_2 , HF'_2 , HF_3 , HF'_3 etc. These filters may be of the broad band type illustrated and described in the Campbell patents above referred to, and are so designed as to transmit a band of frequencies in the neighborhood of the basic carrier frequency assigned to each bridge connection, the band being of sufficient width to allow for the 90 variation in frequency corresponding to the low frequency signaling currents. 95

The bridge connection 1—1' is associated through a transformer 11 with transmitting channel TL_1 and receiving channel RL_1 , in 100 which are included the necessary translating devices for translating the low frequency signals into carrier currents and vice versa. The channels TL_1 and RL_1 are associated with the low frequency signaling line L_1 through a transformer 11', the line L_1 being balanced by an artificial line or network N_1 , in order to render the channels TL_1 and RL_1 conjugate with respect to each other. 110

The transmitting channel TL_1 includes a modulator M_1 , a band filter TF_1 and an amplifier TA_1 . The modulator M_1 may be any suitable arrangement for modulating carrier frequencies in accordance with signals, 120 130

such for instance, as the well known vacuum tube modulator. As modulators of this character are commonly understood in the art, the details of this apparatus are not 5 illustrated, and it is merely indicated schematically. The filter TF_1 is a broad band filter similar in structure to, and transmitting a range of frequencies the same as, the filters HF_1 and HF'_1 . The amplifier 10 TA_1 may be of any well known character, but is preferably a vacuum tube amplifier of well known type, and as the details of such amplifiers are well known and constitute no part of the present invention, the amplifier 15 is merely indicated schematically.

The receiving channel RL_1 includes a detector D_1 , an amplifier RA_1 and a band filter RF_1 . The detector D_1 may be any well known detecting arrangement for translating 20 carrier currents into low frequency signaling current, and is preferably a detector of the well known vacuum tube type. As the detail of this structure forms no part of the present invention, the detector is indicated 25 schematically. The amplifier RA_1 may be of any well known type, such, for instance, as the vacuum tube amplifier, and is likewise illustrated schematically, as the details of such amplifiers are well known and constitute 30 no part of the present invention. The filter RF'_1 is a band filter of the type illustrated in the Campbell patents hereinbefore disclosed, and is preferably so designed as to transmit a range of frequencies corresponding 35 to the range of low frequency signaling currents employed in transmitting signals over the line L_1 .

The lines L_2 and L_3 are associated with the bridge circuits 2-2' and 3-3' respectively 40 by means of transmitting and receiving carrier channels, including apparatus similar to that just described. The filters RF'_2 and RF'_3 of the receiving channels RL_2 and RL_3 , respectively are similar to the filter RF'_1 . The filter TF_2 of the transmitting channel TL_2 is similar to filters HF_2 and HF'_2 , while the filter TF_3 of the transmitting channel TL_3 is similar to the filters HF_3 and HF'_3 . The operation is as follows:

50 Signaling currents from the line L_1 are transmitted through the transformer 11 and modulate carrier currents of the frequency assigned to the bridge connection 1-1' in a well known manner. The modulated carrier currents are then transmitted through the filter TF_1 , are amplified by the amplifier TA_1 and impressed upon the bridge connection 1-1' at the mid points of the windings of the transformer 11. The transmitted 55 energy divides, half flowing through the filter HF_1 over the circuit 1 to the main line ML and the other half flowing through the filter HF'_1 over the circuit 1' to the artificial line MN . Owing to the bridged relation of 60 the circuits 1-1', 2-2' and 3-3', this trans-

mitted energy is balanced with respect to all the receiving channels so that substantially no interference is produced. By means of the frequency separation due to the filters HF_1 , HF'_1 etc., interference between both 70 receiving and transmitting channels is further reduced. It will be understood, of course, that signals incoming from the line L_2 and L_3 will modulate the carrier frequencies assigned to the bridge circuits 75 2-2' and 3-3' respectively, and may be impressed upon the line ML simultaneously with the currents from the line L_1 without producing interference.

Carrier currents modulated in accordance 80 with signals at a distant station, and transmitted over the line ML are selected by means of the filters HF_1 , HF'_1 and HF_3 into the corresponding bridged circuits, and pass through the transformers 11, 12 and 13 to the receiving channels RL_1 , RL_2 and RL_3 respectively. The modulated carrier frequencies thus transmitted by the circuit RL_1 are detected by the detector D_1 in a well known manner, the resulting low frequency 85 signaling currents being then amplified by the amplifier RA_1 and transmitted through the band filter RF'_1 to the line L_1 . Similar operations may simultaneously take place 90 with respect to the receiving channels RL_2 and RL_3 .

Fig. 6 illustrates the manner in which the bridged arrangement of circuits may be utilized for preventing interference between low frequency signaling currents and high 100 frequency carrier currents where a carrier system is superposed upon an ordinary low frequency signaling line. In this figure, ML denotes a transmission line over which low frequency signal transmission and carrier 105 transmission may simultaneously take place. The main line ML is associated with a balancing artificial line or network MN through a low frequency bridge connection 100-100' and through a high frequency or carrier 110 bridge connection 200-200'. The low frequency bridge circuits 100-100' include low pass filters LF and LF' respectively. These low pass filters are of the general type disclosed in the patents to Campbell above referred to, and are adapted to transmit a range of frequencies from zero up to the highest frequency utilized in connection with the transmission of low frequency signals from the terminal signaling line LT , 115 which, as illustrated, is connected to the junction point of the circuits 100-100'. Line LT may be an ordinary terminal telephone circuit including the usual composite apparatus etc. (not shown). The carrier bridge circuits 200-200' include high pass filters HF and HF' respectively. These filters are of the type illustrated in the 120 patents to Campbell above referred to, and are so designed as to transmit all frequencies 130

above a lower limiting frequency which is so chosen as to be above the highest frequency transmitted over the terminal line LT.

5 A common carrier transmission circuit TL, and a common carrier receiving circuit RL, are associated with the bridge circuits 200—200' through a balanced transformer arrangement 20, the connections being such 10 that the circuits TL and RL are conjugate with respect to each other. The circuit TL has associated therewith, transmitting channels TL₁, TL₂, etc., corresponding to signaling lines which may be similar to the lines 15 L₁, L₂ etc. of Fig. 5. The circuit RL has associated therewith carrier receiving channels RL₁, RL₂, etc. corresponding to the same lines. The association of the carrier receiving and transmitting channels with 20 the low frequency signaling lines may be through transformer arrangements similar to the transformers 11', 12', etc. of Fig. 1, but for simplicity these connections are not illustrated. Transmitting channels TL₁ and 25 TL₂ include band filters TF₁ and TF₂ so designed as to transmit a band of frequencies in the neighborhood of the carrier frequency assigned to each channel, the width of the band being sufficient to take care of 30 the frequency variations corresponding to the low frequency signals. Similar band filters RF₁, RF₂ are included in the receiving channels RL₁, RL₂ etc.

The operation is as follows: The energy 35 of low frequency signals incoming from the terminal line LT divides between circuits 100 and 100', half flowing through the filter LF to the main line ML; the other half flowing through the filter LF' to the balancing 40 network MN. Owing to the bridged relation of the circuits 100—100' and 200—200' such portion of this energy as gets through filters HF and HF' is substantially without effect upon the receiving circuit RL and consequently no interference with the receiving 45 channels RL₁, RL₂ by low frequency signals from the terminal line LT results. Low frequency signaling currents incoming from the line ML pass through the filter LF to 50 the line LT, being substantially prevented from entering the carrier apparatus associated with circuit 200 by means of the high frequency filter HF.

Interference with the low frequency signaling 55 currents of circuit LT by the higher frequency carrier currents of circuit TL may be prevented by reversing the wires of bridge connection 100 or 100' and for this purpose a switch is shown in the connection 60 100. Under this condition carrier currents from the transmitting channel TL₁ pass through the filter TF₁ and are transmitted through the transformer 20 to the bridge circuit 200—200'. Owing to the bridged relation 65 between the carrier apparatus and the

apparatus associated with the terminal line LT, together with the filtering action of the filters LF and LF', the carrier energy is substantially without effect upon said line LT, but passes through the filter HF to the main line ML. Carrier currents received over the line ML are transmitted through the high pass filter HF into the circuit 200 and from this into the receiving circuit RL where they are selected by means of the filters RF₁, 70 RF₂ etc. to the receiving channels RL₁, RL₂, etc. Owing to the differential connection between circuits RL and TL, the received carrier currents do not react upon the transmitting channels TL₁ and TL₂ etc. 75

Fig. 7 shows an arrangement in which each carrier channel is associated with the main line ML through the balanced bridge arrangement, while the balanced bridge connection is also employed for the low frequency terminal line LT. This arrangement differs from that of Fig. 6 merely in that the transmitting and receiving channels of each carrier circuit are rendered conjugate through the balanced bridge arrangement 80 instead of securing conjugacy by means of the differential connection employed in Fig. 6. Instead of designing the network MN in Fig. 7 to balance the main line ML at all frequencies, this network may be merely designed to balance said line at the low frequencies transmitted from the terminal line LT in which case separate networks MN₁ and MN₂ may be employed for balancing the line ML with regard to the carrier frequencies assigned to the channels associated with 85 the bridge connections 1—1', 2—2' etc. The operation of this circuit will be obvious from the operation described in connection with previous circuits, and need not be further considered. 90

Fig. 8 illustrates an arrangement in which low frequency telephone currents, Morse signaling currents, low frequency alternating telegraph currents and a plurality of 95 high frequency carrier channels are superposed upon a common transmission line, the Morse and low frequency alternating current systems being associated with the remaining circuits by a differential connection, while the telephone and high frequency carrier channels are connected in multiple bridged relation. As shown, the terminal telephone line LT is associated through a transformer 10' with a transmitting channel T and a receiving channel R which are rendered conjugate with respect to each other by balancing the terminal line by means of a network NT. The channels T and R are associated with the bridge connection 100—100' through 110 a balanced transformer arrangement 10. The several high frequency carrier channels are similarly associated with the bridge connections 1—1', 2—2', 3—3' by means of 115 transformers 11, 12 and 13. Instead of in- 120

cluding the filters for the high frequency channels in the bridge circuits, as in Figs. 5 and 7, such filters are included in the carrier transmitting and receiving channels in Fig.

8. Thus in the transmitting channel TL_1 , a filter TF_1 is inserted, while in the receiving channel RL_1 , a filter RF_1 is included. In order to increase the selectivity, each carrier transmitting channel may be arranged to 10 transmit at a different frequency from the corresponding receiving channel; thus the transmitting frequencies of the transmitting channels TL_1 , TL_2 and TL_3 may be 2500, 2800 and 3100 cycles respectively; while the corresponding receiving frequencies for the channels RL_1 , RL_2 and RL_3 may be 3600, 3900 and 4200 cycles respectively.

The transmitting and receiving channels T and R of the terminal line LT are provided with filters TF and RF adapted to transmit frequencies lying within the ordinary telephonic range, while suppressing frequencies above and below such range. If desired, amplifiers TA and RA may be included in the circuits T and R as indicated schematically. These amplifiers may, of course, be of any well known type, such as a vacuum tube amplifier. Branch circuits BM and BC are connected to the midpoints 20 of the windings of the transformer 10 in the same manner as the transmitting channel T of the telephone circuit, these branch circuits being thus differentially connected to the remaining circuits in order to facilitate superposition of a Morse telegraph system and a low frequency alternating current telegraph system upon the transmission line ML. A band filter FC is included in the circuit BC for transmitting the frequencies assigned to the alternating current telegraph channel, and a band filter FM is included in the circuit BM for transmitting Morse frequencies. The Morse circuit may include a differential receiving relay DR having an armature 30 whose contacts control the Morse receiving circuit RM. The Morse transmitting circuit TM is connected to the midpoints of the differential relay DR. In order to render the transmitting and receiving Morse channels conjugate, the filter FM is balanced by means of a filter FM', while a network NM is provided to balance the circuits beyond the filter FM.

The alternating current telegraph apparatus may comprise a transmitting circuit TC and a receiving circuit RC associated with the branch BC through a transformer TT. These circuits may be rendered conjugate by balancing the filter FC by means of an equivalent filter FC', and by providing a balancing network NC for balancing the circuit beyond the filter FC.

The operation of the high frequency carrier channels 1, 2 and 3 will be apparent 60 from the description of the operation of

similar apparatus in connection with previously described modifications, it being remembered that while in the case illustrated transmission and reception for a given channel takes place at different frequencies they 70 may be at the same frequency providing the duplex balance is sufficiently good. Incoming currents from the telephone line LT are transmitted to the channel T, amplified by the amplifier TA, and are then passed 75 through the filter TF to the line ML. Low frequency telephone currents incoming from the line ML are transmitted through the transformer 10 and pass through the filter RF to the receiving circuit R. After being 80 amplified by the amplifier RA, such telephone currents are transmitted through the transformer 10' to the line LT.

Low frequency alternating currents from the telegraph channel TC are transmitted 85 through the transformer TT and pass through the filter FC over the branch BC to the mid points of the windings of the transformed 10, the energy being then divided, one-half of the higher frequency interference tending components being transmitted to the line ML and the other half to the balancing network MN. Since this current is applied to the mid points of the windings of the transformer 10, no reaction is 90 caused in any of the receiving channels such as the telephone receiving channel R, or the carrier receiving channels RL_1 , RL_2 etc. Alternating telegraph currents received from the line ML pass into the branch BC to which they are admitted by the filter FC, the filters 100 associated with the other channels substantially preventing such currents from reacting upon the other channels. From the branch BC the currents are transmitted to 105 the receiving channel RC.

Morse currents from the transmitting circuit TM are applied to the mid points of the windings of the differential relay DR without operating said relay, and are then transmitted through the filter FM over the branch BM and are then applied to the mid points of the windings of the transformer 10, so that they do not react in the receiving 110 channels R, RL_1 etc. Morse currents received from the line ML pass into the branch BM owing to the action of the filter FN, being suppressed from the other channels by means of the filters therein. The received 115 Morse currents in the branch BM flow serially through the windings of the differential relay DR and actuate such relay to transmit the signals to the Morse receiving circuit RM.

While the invention has been embodied in 120 certain circuit arrangements which are considered desirable from a practical standpoint, it will be obvious that the general principles herein disclosed may be embodied 125 in many organizations widely different from 130

those illustrated, without departing from the spirit of the invention as defined in the following claims.

What is claimed is:

- 5 1. In a multiplex signaling system, a transmission circuit, a balancing means therefor, a plurality of receiving devices and a plurality of transmitting devices, selective means discriminative between different 10 alternating current frequencies for maintaining frequency separation between different sets of transmitters and receivers, and separate means for simultaneously associating each of said receiving devices with said 15 transmission circuit and said balancing means, said transmitting devices being so associated with said transmission circuit and said balancing means that energy from said transmitting devices will be applied to 20 points neutral with respect to said receiving devices. 70
2. In a multiplex signaling system, a transmission circuit, a balancing means therefor, a plurality of receiving devices and a plurality of transmitting devices, selective means discriminative between different alternating current frequencies for maintaining frequency separation between different sets of transmitters and receivers, and separate means for simultaneously associating each of said receiving devices with said transmission circuit and said balancing means, said transmitting devices being so associated with said transmission circuit and said balancing means that energy from said transmitting devices will produce substantially no effect upon the corresponding receivers. 75
3. In a multiplex signaling system, a transmission circuit, balancing means therefor, a plurality of parallel connections between said circuit and balancing means, a plurality of transmitters and receivers, selective means discriminative between different alternating current frequencies for maintaining frequency separation between different sets of transmitters and receivers, circuit connections for simultaneously associating a transmitter and receiver with each of said parallel connections, said circuit connections being such that energy supplied from any one of said transmitters to said transmission circuit will be substantially without effect upon the corresponding receiver. 80
4. In a multiplex signaling system, a transmission circuit, balancing means therefor, a plurality of parallel connections between said circuit and balancing means, a plurality of transmitters and receivers, selective means discriminative between different alternating current frequencies for maintaining frequency separation between different sets of transmitters and receivers, circuit connections for simultaneously associating a transmitter and receiver with each of said parallel connections, said circuit connections being such that energy supplied from any one of said transmitters to said transmission circuit will be substantially without effect upon any of said receivers. 85
5. In a multiplex signaling system, a transmission circuit, balancing means therefor, a plurality of parallel connections between said circuit and balancing means, transmitting and receiving elements for each parallel connection, a transformer balanced to establish conjugate circuits associating one of said elements with the corresponding parallel connection, the other of said elements being so associated with said parallel connection that energy from the transmitter will produce substantially no effect upon the receiver. 90
6. In a multiplex signaling system, a transmission circuit, balancing means therefor, a plurality of parallel connections between said circuit and balancing means, transmitting and receiving elements for each parallel connection, a transformer balanced to establish conjugate circuits associating one of said elements with the corresponding parallel connection, the other of said elements being so associated with said parallel connections that energy from the transmitter will produce substantially no effect upon any of the receivers associated with said multiple connections. 95
7. In a multiplex signaling system, a transmission circuit, balancing means therefor, a plurality of parallel connections between said circuit and balancing means, transmitting and receiving elements for each parallel connection, a transformer balanced to establish conjugate circuits associating one of said elements with the corresponding parallel connection, the other of said elements being connected to points of said parallel connection which are neutral with respect to said first element. 100
8. In a multiplex signaling system, a transmission circuit, a balancing means therefor, a plurality of receiving channels and a plurality of transmitting channels, selective means discriminative between different alternating current frequencies, associated with said channels for maintaining frequency separation between said channels, and separate means for associating each of said receiving channels with said transmission circuit and said balancing means, said transmitting channels being so associated with said transmission circuit and said balancing means that energy from said transmitting channels will produce substantially no effect upon said receiving channels. 105
9. In a multiplex signaling system, a transmission circuit, a balancing means therefor, a plurality of receiving channels 110
- 65 120
- 65 125
- 65 130

and a plurality of transmitting channels, filters discriminative between different alternating current frequencies associated with said channels for maintaining frequency separation between said channels and separate means for associating each of said receiving channels with said transmission circuit and said balancing means, said transmitting channels being so associated with said transmission circuit and said balancing means that energy from said transmitting channels will produce substantially no effect upon said receiving channels.

10. In a multiplex signaling system a transmission circuit, balancing means therefore, a plurality of parallel connections between said circuit and balancing means, a transmitting apparatus and a receiving apparatus for each parallel circuit associated therewith in conjugate relation with respect to each other, and selective means connected between each transmitting and receiving apparatus and the corresponding parallel connection.

25 11. In a multiplex signaling system, a transmission circuit, balancing means therefore, a plurality of parallel connections between said circuit and balancing means, a transmitting and receiving circuit including transmitting and receiving apparatus respectively associated with each parallel connection in conjugate relation with respect to each other, and selective means in said transmitting and receiving circuits.

35 12. In a multiplex signaling system, a transmission circuit, balancing means therefore, a plurality of parallel connections between said circuit and balancing means, transmitting and receiving elements for each 40 parallel connection, a transformer for associating one element of each pair with the corresponding parallel connection, the other of each pair being associated with the corresponding parallel connection in conjugate relation with respect to the first element, and

selective means between the transmitting and receiving elements and their points of association with said parallel connections.

13. In a multiplex signaling system, a transmission circuit, balancing means therefore, a plurality of parallel connections between said circuit and balancing means, transmitting and receiving circuits for each parallel connection including transmitting and receiving elements respectively, a transformer for associating one circuit of each pair with the corresponding parallel connection, the other circuit of each pair being conjugately associated with the corresponding parallel connection, and selective devices included in said transmitting and receiving circuits between the transmitting and receiving elements and the points of association of the circuits with said parallel connections.

20 14. In a multiplex signaling system, a transmission circuit, balancing means therefore, a plurality of parallel connections between said circuit and balancing means, a pair of circuits, one for transmitting and one for receiving, associated with each parallel connection, and a plurality of signaling channels associated with at least one circuit of each pair which is associated with one of said parallel connections.

25 15. In a multiplex signaling system, a transmission circuit, balancing means therefore, a plurality of parallel connections between said circuit and balancing means, a pair of circuits, one for transmitting and one for receiving, associated with each parallel connection, a plurality of transmitting channels associated with the transmitting circuits of at least one pair, and a plurality of receiving channels associated with the receiving circuit of said pair.

In testimony whereof, I have signed my name to this specification this 26th day of August 1919.

LLOYD ESPENSCHIED.
